UNITED STATES PATENT OFFICE.

JOHN W. BELL, OF COVINGTON, KENTUCKY, ASSIGNOR TO MURPHY IRON WORKS, OF DETROIT, MICHIGAN, A CORPORATION OF MICHIGAN.

STOKER-DRIVING ARM.

1,244,945.

Specification of Letters Patent

Patented Oct. 30, 1917.

Application filed July 9, 1914. Serial No. 849,884.

To all whom it may concern:

Be it known that I, JOHN W. BELL, a citizen of the United States of America, residing at Covington, in the county of Kenton 5 and State of Kentucky, have invented certain new and useful Improvements in Stoker-Driving Arms, of which the following is a specification, reference being had therein to the accompanying drawings.

10 In the operation of automatic furnace stokers where a plurality of feeding members is reciprocated by means of an operating shaft and suitable driving mechanism therefor, when the feed becomes clogged or 15 any of the feed devices are prevented from operation in any way, parts of the mechanism are broken due to the fact that the driving mechanism is positively actuated by means of a motor. The object of this invention is to prevent such breakages by simple and convenient means which may be readily readjusted and repaired without great loss of time or expense. To this end the invention consists in embodying in the driving 20 mechanism, an arm made in two parts connected by means adapted to be disrupted under abnormal strain applied to the arm and so constructed as to be readily replaced.

To this end the invention consists in the 25 matters hereinafter set forth and more particularly pointed out in the appended claims, reference being had to the accompanying drawing, in which—

Figure 1 is a front elevation of a portion 30 of a furnace front with portions broken away to show the internal construction of the stoker mechanism embodied therein and showing devices embodying the invention in operative position in connection with the 35 stoker driving mechanism; and

Fig. 2 is a perspective view of a device 40 embodying the invention.

The invention is shown as applied to an old and well known automatic stoker construction, but it will be understood that the 45 same may be applied as well to other forms and constructions of driving mechanisms without departing from the spirit of this invention.

50 The automatic stoker illustrated in Fig. 1 comprises a suitable feed hopper or magazine 1 at each side of a fire chamber 2 and beneath each magazine which has an inclined discharge throat is a coking plate 3.

55 Upon each coking plate is reciprocable a se-

ries of stoker boxes 4 for pushing the fuel across the coking plate on to the upper ends of the inclined grate bars 5. The stoker boxes are reciprocated by means of segments 6 secured upon shafts 7 extending longitudinally beneath the several stoker boxes with their forward ends projecting through the furnace front plate 8 in which are suitable doors through which access may be had to the interior of the furnace.

60 To turn the rock shafts 7 and reciprocate the stoker boxes, a longitudinally reciprocable bar 9 is mounted in suitable bearings upon the front plate and this bar is driven by means of a connecting rod 10 pivotally attached at one end to the bar and at its opposite end to a drive wheel 11 adapted to be actuated in any suitable manner as by a steam engine (not shown).

65 Secured upon the outer squared end of each shaft 7 is a suitable crank arm 12 embodying this invention and each of these crank arms is connected to the driving arm 9 by means of a link 13, all of the parts being arranged in an old and well known manner. Other shafts such as a clinker bar 14 and grate bar actuating shafts 15 are also shown as being turned by means of the driving bar 9 through the medium of crank arms 16 and 17. If found desirable, the 70 crank arm 12 embodying the invention may be substituted for the arms 16 or 17 to prevent breakage of the shafts 14 or 15 or the parts actuated thereby.

75 Each of the arms 12 comprises a member 18 formed with an opening or socket 19 at one end of rectangular outline in cross section to fit over the angularly formed outer end of the shaft 7 and secured thereto. The 80 opposite or free end of the member 18 is 85 provided with two transverse openings arranged at a distance apart and in the longitudinal center line of the member near said end.

85 An end member 20 of the arm is bent into 90 U-shape to embrace the free end of the member 18 and is formed with openings to register with the openings in said member. A bolt 21 passing through one of the openings in the member 18 and the aligned openings in 95 the loop, pivotally attaches the loop to the arm so that it may swing thereon. A pin 22 is inserted through the other opening in the member 18 and through the aligned openings 100 in the loop to hold the end member or loop 110.

20 in longitudinal alinement with the member 18 and prevent its turning relatively thereto. The pin 22 is made from a comparatively fragile material such as wood so
5 that when a very heavy strain is put upon the arm by the link 13 which is hooked into the loop for transmitting motion from the bar 9 to the shaft 7, the pin 22 will be sheared off and permit the loop end of the
10 arm to turn upon its pivotal connection with the main portion of the arm without turning the shaft 7. The strength of tie pin 22 is such that under normal conditions it will hold the loop against turning upon the
15 member 18, of the arm and will transmit sufficient power to turn the shaft 7 and reciprocate the stoker boxes, but when the stoking mechanism is prevented from actuation by becoming clogged or from any other
20 cause, the resistance offered to the turning of the shaft 7 will break the pin and the strength of this pin is such that it will break before any of the driving mechanism or stoker parts will be broken by the actuation
25 of the driving mechanism.

Obviously changes may be made in the construction and arrangement of the driving arm embodying this invention, without

departing from the spirit of the invention and I do not therefore wish to limit myself 30 to the particular form or construction shown.

Having thus fully described my invention what I claim is:—

An automatic stoker including feeding mechanism, a rock shaft for driving said mechanism, a driving bar, power means for operating the driving bar, and a connecting arm on the shaft for connecting said shaft to said bar, a bar comprising a main member and a U-shaped end member embracing the free end of said main member, said main member and end member being provided with two sides of alined transverse openings, a bolt passing through one set of alined openings to form a pivotal connection between said member, and a pin formed of fragile material engaging the other set of openings to normally prevent the end member from turning upon the main member. 45

In testimony whereof I affix my signature 50 in presence of two witnesses.

JOHN W. ^{his} X BELL.
